UNITED STATES PATENT OFFICE.

OTTO L. HERMANN, OF ST. LOUIS, MISSOURI, ASSIGNOR TO CORBON L. HARVEY, OF DETROIT, MICHIGAN.

LEDGER RACK.

Application filed January 21, 1926. Serial No. 82,756.

My invention relates to bookkeeping equipment and consists in an improved rack intended to be used for open ledgers of the loose leaf type.

5 In my copending application Serial No. 616,527, I illustrate and describe a somewhat similar ledger rack and my present invention consists in improvements upon the rack shown in the above-mentioned application.

10 One of the objects of my present invention is to provide a support for one ledger back and the leaves resting thereon, which support may be adjusted in height according to the quantity of leaves in the ledger. For instance, when a ledger is first used and contains a small quantity of leaves, it is a marked convenience to have the same at a certain height and when more leaves are added to the ledger it is desirable to be able 20 to lower the back of the ledger so that the height of the leaves will be maintained at about the same level.

Manufacturers and retailers of office equipment of the nature referred to have 25 frequently found it advantageous to stock ledger racks of two different sizes in order to accommodate the conditions just mentioned. With my invention, a single rack is adapted to satisfy the demand which heretofore has been satisfied by the provision of 30 different sized racks. In a ledger rack of the type described, it is desirable to have a guide for the top edges of the leaves which are turned from one ledger back to the other, and another object of my present invention 35 is to provide a guide for the top edges of the leaves which may be adjusted to the movable ledger support as the latter is varied in height.

40 In the accompanying drawings illustrating a selected embodiment of my invention—

Figure 1 is a front elevation of a ledger rack with one of the ledger back supporting surfaces located in an elevated position.

45 Figure 2 is a vertical transverse section taken substantially on line 2—2 of Figure 1.

Figure 3 is a front elevation of the rack with the movable support in a lower position than that shown in Figure 1 and with 50 a ledger indicated in dot-and-dash lines.

Figure 4 is an isometric of the member used to position the movable ledger back supporting element when the higher position is desired.

55 Fig. 5 is a vertical transverse section of

the groove for holding the upper edge of the back of a ledger, in the same relation as Fig. 2.

The rack comprises a base 1 which is divided into ledger back supporting parts by a vertical partition 2, the righthand face of which is inclined from the vertical. At the rear of the lefthand portion of the base a permanent wall 3 joins the base to partition 2 and a cleat 4 on wall 3 provides a groove 60 5 for receiving and frictionally retaining the upper edge of the back of the ledger which is resting on the lefthand portion of the base.

On the righthand portion of the base 1 mount a rectangular frame 6 and position 70 the latter on the base by means of dowels 7 which fit into recesses 8 provided in the base. The upper and lower edges of frame 6 are located in parallel planes and the upper edges are provided with recesses 9 corresponding to the recesses 8 in the base. 75

Carried on frame 6 is the righthand ledger back supporting member 10, the upper surface of which is inclined at an angle to the horizontal so that it will be substantially at 80 right angles to the righthand surface of partition 2. The bottom edges of member 10 are provided with dowels 11 which fit into the recesses 9 in the top edges of frame 6.

At the rear of member 10 I provide a wall 85 12 which has a recess 13 corresponding to the recess 5 in wall 3. This serves to receive the top edge of the back of the ledger resting on member 10 and it will be understood that the top edges of the leaves on this back 90 will be engaged and positioned by the front surface of cleat 14 of wall 12.

To guide the ledger leaves as they are turned from one side to the other, I provide a channel-shaped element 15 of thin metal 95 and pivot the same to an upward projection 16 on the rear end of partition 2. The outer or swinging end of element 15 fits over the top of wall 12.

When the ledger leaves are increased in 100 number to such an extent that it is inconvenient to have the ledger supported at such a height as is indicated by the arrangement shown in Figure 1, the frame 6 may be removed and the member 10 mounted directly 105 on the righthand portion of the base 1 in which case the dowels in member 10 will enter the recesses 8 in the base, the dowel recesses being so positioned that the lefthand 110 edge of member 10 will contact with the

righthand face of partition 2. When the ledger back supporting member is in the lowered position as indicated in Figure 3, the rear guide element 15 swings downwardly and fits over the rear wall 14 in the same manner as indicated in Figure 1.

An additional feature of my invention is the provision of removable strips 4^a and 14^a on the underfaces of cleats 4 and 14. I have 10 shown these strips and cleats as having tongue and groove joints and the friction of these joints will retain the strips in place unless they are intentionally removed. If it is desired to use a ledger back of leather and 15 corduroy, or other material of unusual thickness, the strips 4^a and 14^a may be removed and the height of recesses 5 and 13 increased accordingly so as to accommodate the thicker ledger back. This arrangement adapts the 20 ledger rack for ledgers of different makes and increases its field of usefulness.

Obviously, the separable strip may be applied in other ways than by the tongue and groove joint illustrated.

I am aware that ledger racks having hinged ledger back supporting boards have been provided heretofore, but with these devices the relation of the ledger leaves to the horizontal is changed with every adjustment 30 and the device does not provide a ledger support which varies in height but at the same time maintains a predetermined angle to the horizontal.

Obviously, the details of my invention may 35 be varied without departing from the spirit thereof and I contemplate the exclusive use of such variations as come within the scope of my claims.

I claim:

40 1. In a ledger rack, a base, an upright partition dividing said base into two parts, a ledger back supporting member removably mounted directly on said base independently of said partition and at one side of said partition and inclined to said base, and a spacing element for insertion between said member and base to support said member at spaced points to adjust the rack for different thicknesses of ledgers.

45 2. In a ledger rack, a horizontal base with dowel recesses, an upright partition thereon having a face inclined from the vertical, a frame resting on said base but removable

therefrom with upper and lower edges in parallel planes, dowels on the lower edges of 55 said frame fitting in said recesses, a member for supporting a ledger back and having its lower edges resting on the upper edges of said frame, dowels in said member fitting into pockets in the upper edges of said 60 frame, the top of said member being inclined to the horizontal, said frame being removable from said base and member and said member being adapted to rest on said base with its dowel fitting in said base recesses. 65

3. In a ledger rack, a base, a transverse upright partition thereon, a support for one back of an open ledger on one side of said partition, said support being adjustable in height, a rear wall on said support for engaging leaves of a ledger on said support, and a ledger leaf guide element having a single pivotal connection to the rear end of 70 said partition, the outer end of said element being adapted to engage said wall irrespective of the height of the latter. 75

4. In a ledger rack, a base, a transverse upright partition thereon, an upstanding projection at the rear of said partition, a support for one back of an open ledger at 80 one side of said partition, said support being adjustable in height, a rear wall for said support, and a channel-shaped ledger guide of thin metal, having one end fitting over said projection and pivoted thereto and having 85 its other end fitting over said wall and slidable thereon.

5. In a ledger rack of the class described, a ledger back supporting base, a rear wall having a recess for receiving the edge of a 90 ledger back resting on said base, and means for adjusting the height of said recess to accommodate different thickness of ledger backs.

6. In a ledger rack of the class described, a ledger back supporting base, a rear wall for positioning a ledger back resting on said base, a cleat on said wall for overlying the inner face of said back, the underface of said cleat comprising a removable strip whereby the distance between said base and cleat may be varied. 95 100

In testimony whereof I hereunto affix my signature this 5th day of Jany, 1926.

OTTO L. HERMANN.
